UNITED STATES PATENT OFFICE.

ANDREW TURNBULL, OF NEW BRITAIN, CONNECTICUT.

DESIGN FOR A PLANE BLOCK FOR CHISELS.

57,748.

Specification for Design.

Patented Apr. 26, 1921.

Application filed June 6, 1919. Serial No. 302,357. Term of patent 3½ years.

To all whom it may concern:

Be it known that I, ANDREW TURNBULL, a citizen of the United States, and a resident of New Britain, in the county of Hartford, State of Connecticut, have invented a new, original, and ornamental Design for a Plane Block for Chisels, of which the following is a specification, reference being had to the accompanying drawings forming part thereof.

In the drawings—

Figure 1 is a view in side elevation of a plane block showing my new design.

Fig. 2 is a top plan view of said design, and

Fig. 3 is an end view thereof.

The surfaces designated in the drawings by the letters *a* and *b* are shaded to indicate that they are polished metal surfaces.

I claim:

The ornamental design for a plane block for chisels as shown.

ANDREW TURNBULL.
